UNITED STATES PATENT OFFICE.

HARRY E. SINGLETON, OF PROVIDENCE, RHODE ISLAND, ASSIGNOR TO BRUNCE E. LOCKWOOD, OF PROVIDENCE, RHODE ISLAND.

DESIGN FOR A CLASP.

46,009.

Specification for Design.

Patented June 23, 1914.

Application filed March 30, 1914. Serial No. 828,406. Term of patent 7 years.

To all whom it may concern:

Be it known that I, HARRY E. SINGLETON, a citizen of the United States, residing at Providence, in the county of Providence and State of Rhode Island, have invented a certain new, original, and ornamental Design for a Clasp, of which the following is a specification.

In the accompanying drawing which forms a part of this specification, the figure

is a perspective view of a clasp showing my design.

I claim,—

The ornamental design for a clasp, as shown.

HARRY E. SINGLETON.
